LOG-PEELING MACHINE HAVING ROCK-
ABLY MOUNTED FLAIL-CARRYING
SHAFT

Robert J. Carpenter, West Enterprise, Miss.

Application February 5, 1953, Serial No. 335,235

4 Claims. (Cl. 144—208)

1

This invention relates to a log peeling or rossing machine and is an improvement over the structure embodied in my prior Patent No. 2,601,261, issued June 24, 1952, for Angularly Adjustable Feed Rolls for Log Peeling or Rossing Machine.

An object of this invention is to provide in a log peeling machine an improved means for supporting the flail whereby logs of irregular shape may be easily debarked or peeled.

Another object of this invention is to provide in a log peeling machine a pair of rockable flail supporting levers, a flail shaft with bearings at each end of the shaft and means pivotally mounting the bearings on the forward ends of the levers so that each lever may rock independent of the other lever.

A further object of this invention is to provide a log peeling machine which is of relatively simple construction so that the various parts may be made rugged and strong enough to withstand rough usage.

With the above and other objects in view, my invention consists in the arrangement, combination and details of construction disclosed in the drawings and specification, and then more particularly pointed out in the appended claims.

In the drawings:

Figure 1 is a detailed end elevation of a log peeling machine constructed according to an embodiment of this invention.

Figure 2 is a fragmentary sectional view taken substantially on the line 2—2 of Figure 1.

Figure 3 is a fragmentary sectional view taken substantially on the line 3—3 of Figure 2.

Figure 4 is a sectional view taken on the line 4—4 of Figure 2.

Figure 5 is a fragmentary sectional view taken on the line 5—5 of Figure 1.

Figure 6 is a fragmentary sectional view taken on the line 6—6 of Figure 3.

Figure 7 is a fragmentary sectional view taken on the line 7—7 of Figure 5.

Figure 8 is a plan view, partly broken away, showing the flail and support therefor.

Figure 9 is a fragmentary sectional view showing the flail regulating means in locked or servicing position.

Referring to the drawings, the numeral 10 designates generally a base frame structure which has mounted therein a log rolling and log moving mechanism generally designated as 11. The log rolling and moving mechanism 11 is more specifically shown in my prior patent supra.

The frame 10 has disposed at the rear side 55

2

thereof upright supports 12 connected across the top by an angle-shaped connecting bar 13. A power member 14 is carried by the frame 10 and includes a drive shaft 15 having a pulley 16 about which an endless belt 17 engages. The belt 17, as shown in Figure 8, engages about a pulley 18 fixed to a shaft 19 journaled in bearings 20 which are carried by the upright members 12.

A pair of elongated levers 21 are rockably mounted on the shaft 19 and a flail generally indicated at 22 is fixed to a shaft 23 which is journaled in bearings 24. The bearings 24, as shown in Figures 5 and 7, include an inner member 25 which is angularly movable relative to an outer housing 26, which is secured by fastening means 27 to a lever 21. In this manner each lever 21 may rock independently of the other lever so that the chains 28 which form part of the flail 22 may engage logs of irregular conformations.

Each lever 21 has extending from the rear thereof a balance carrying bar 30 on which a weight 31 is adjustably mounted. Each lever at the forward end thereof has secured thereto a downwardly and outwardly projecting guard member 32, and a laterally projecting plate 33 extends from each lever 21. Lugs 31' depending from plate 33 carry log riding rollers 34.

The shaft 19 also has fixed thereto a pulley 35 for each lever 21 and a belt 36 is trained about the pulley 35 and about a forward pulley 37 mounted one on each end of the flail shaft 23. The two levers 21 engage on the outer sides of a pair of upright guide bars 38 which are fixed at their lower ends to the frame 10 and are secured to the upper rear bar 13 by means of a triangular brace including a pair of rearwardly convergent bracing bars 39.

Each lever 21 has fixed thereto a depending lever 40 which is connected to an upwardly projecting lever 41 by means of a link 42. The lever 41 is fixed to a shaft 43 journaled in bearings 44 carried by the frame 10, and a hand adjusting lever 45 is fixed to the shaft 43. Forward rocking of hand lever 45 will swing lever 40 upwardly and forwardly so as to thereby raise the flail carrying levers 21. Link 42 is formed with an elongated slot 46 through which pivot 47 engages so that each lever 21 may rock upwardly independently of one another.

A dome-shaped guard 48 is disposed above the forward ends of the levers 21 and is supported from outer and inner brackets 49 and 50 carried by the levers 21. The guard 48 is yieldably supported relative to the brackets 49 and 50 by means of springs 51 which engages about bolts 52.

loosely fitting in bolt receiving holes in the arms 48 and 49.

A downwardly and outwardly inclined guard plate 52 is fixed to the forward portion of the guard 47 for deflecting the loosened bark which is projected outwardly by the flail chains 29.

In the use and operation of this device, the log which engages the toothed rolling and feeding members 11 is engaged by the rotating flail chains 29 and the levers 21 are lowered to operative position by rocking the hand lever 45 rearwardly so as to swing levers 40 rearwardly and thereby swing levers 21 downwardly.

In the event the log is uneven as to any portion of the surface thereof, the levers 21 may rock one independently of the other, with shaft 23 rotating at normal speed and the bark on the irregular surfaces of the log will be removed in the normal manner.

When it is desired to service the flail structure or the log feeding means, this may be done without removing the guard 47 by manually raising the outer ends of the levers 21 and swinging hand lever 45 rearwardly until lever 41 bears against the rear of frame 10 as shown in Figure 9. In this position lever 41 is locked and link 42 is also locked so that levers 21 will be held in an extreme upper inoperative or servicing position.

I do not mean to confine myself to the exact details of construction herein disclosed, but claim all variations falling within the purview of the appended claims.

What I claim is:

1. In a log peeling or rossing machine having a frame with means for rotating and moving a log endwise, a flail shaft, a flail member on said shaft, a pair of shaft supporting levers, means rockably supporting said levers from said frame, for independent movement one relative to the other, a bearing for each end of said shaft, and means rockably securing said bearings to said levers.

2. In a log peeling or rossing machine having

a frame with means for rotating and endwise moving a log, a pair of elongated levers rockably carried by said frame, a flail shaft, a bearing on each lever for supporting opposite ends of the flail shaft, means rockably mounting said bearings on said levers for rocking movement of said shaft upon rocking movement of said levers, said flail shaft being rotatable in said bearings, a flail fixed to said shaft, and a dome-shaped guard carried by said levers and extending over said flail.

5 5. In a log peeling or rossing machine having a frame with means for rotating and endwise moving a log, a pair of elongated levers rockably carried by said frame, a flail shaft, a bearing on each lever for supporting opposite ends of the flail shaft, means rockably mounting said bearings on said levers for rocking movement of said shaft upon rocking movement of said levers, said flail shaft being rotatable in said bearings, a flail

10 fixed to said shaft, and a dome-shaped guard carried by said levers and extending over said flail, and downwardly projecting log riding bars carried by the free ends of said levers.

15 6. In a log peeling or rossing machine having a frame with means for rotating and endwise moving a log, a pair of elongated levers rockably carried by said frame, a flail shaft, a bearing on each lever for supporting opposite ends of the flail shaft, means rockably mounting said bearings on said levers for rocking movement of said shaft upon rocking movement of said levers, said flail

20 shaft being rotatable in said bearings, a flail fixed to said shaft, and a dome-shaped guard carried by said levers and extending over said flail, and downwardly projecting log riding bars carried by the free ends of said levers.

25 7. In a log peeling or rossing machine having a frame with means for rotating and endwise moving a log, a pair of elongated levers rockably carried by said frame, means for manually adjusting said levers, a flail shaft, a bearing on each lever for supporting opposite ends of the flail shaft, means rockably mounting said bearings on said levers for rocking movement of said shaft upon rocking movement of said levers, said flail

30 shaft being rotatable in said bearings, a flail fixed to said shaft, and a dome-shaped guard carried by said levers and extending over said flail.
